UNITED STATES PATENT OFFICE

WILLIAM C. MCCOY, OF CLEVELAND, OHIO, ASSIGNOR TO THE CLEVELAND TRUST COMPANY, OF CLEVELAND, OHIO, A CORPORATION OF OHIO

PISTON

Application filed September 7, 1926. Serial No. 133,909.

This invention relates to pistons for internal combustion engines and particularly to flexible skirt pistons that may be formed from suitable aluminum alloys or any other desirable material.

One of the objects of the invention is to provide a piston that requires a minimum degree of care in fitting it to an engine cylinder and that is of inexpensive and simple construction.

Another object of the invention is to provide a piston of the flexible skirt type wherein in the skirt is compressible on its diameters in the general direction of the wrist pin axis and transversely relative thereto.

An additional object of the invention is to provide a flexible skirt piston in which the distortion of the skirt from cylinder wall pressure is more uniform than in previously proposed piston structures.

Another object of the invention is to provide a piston in which the skirt is supported solely from connections to one of its bearing faces, the opposite bearing face being supported solely from connections to the first bearing face and disconnected from other parts of the piston structure.

A further object of the invention is to provide a split skirt piston of balanced weight relative to the axis of the wrist pin.

An additional object of the invention is to provide a piston of such character that it can be conveniently cast in a permanent mold.

These and other objects of the invention will be apparent from a consideration of the accompanying description taken in connection with the drawings, wherein

Figure 1 is an elevational view, looking in the direction of the wrist pin boss, of a piston constructed in accordance with the invention.

Fig. 2 is a bottom plan view of the piston shown in Fig. 1 taken looking into the open end of the piston skirt.

Fig. 3 is a side elevational view of the piston shown in Fig. 1 taken looking in the direction of one of the working or bearing faces thereof.

Fig. 4 is a detail view of a portion of the piston skirt shown in enlarged transverse

cross section taken substantially on line A—A of Fig. 1.

Fig. 5 is a side elevational view of a corresponding piston structure illustrating a modified application of the invention. 55

Fig. 6 is a bottom plan view looking into the open end of the piston shown in Fig. 5.

Fig. 7 is a side elevational view of a piston structure corresponding to the structure shown in Fig. 5 except that no yielding bridge 60 spans the longitudinal slit in the piston skirt.

Fig. 8 is a side elevational view, looking in the direction of a piston boss, of a modified form of the invention in which one side of the skirt is connected both to the piston head 65 and to webs formed integrally with the piston bosses.

Fig. 9 is a side elevational view, looking in the direction of the slit working face of the piston shown in Fig. 8. 70

Fig. 10 is a bottom plan view of the piston shown in Fig. 8 and Fig. 9 looking into the open end of the piston skirt.

Fig. 11 is a side elevational view of a corresponding piston in which a yielding bridge 75 spans the longitudinal slot in the piston skirt and in which both working faces of the piston are separated from the piston head.

Fig. 12 is a side elevational view of the piston shown in Fig. 11. 80

Fig. 13 is a side elevational view of a further modification of the invention in which both working faces of the piston skirt are separated from the head by a transverse slot and in which the supported working face of the piston is reinforced by a chordal rib and extends transversely thereacross. 85

Fig. 14 is a view looking into the open end of the piston shown in Fig. 13.

Fig. 15 is a side elevational view of a piston in which the supported working face of the piston is transversely stiffened and in which the longitudinal slit in the skirt is offset from both the working face of the piston and the piston boss; and 90

Fig. 16 shows the general form of piston illustrated in Fig. 15 with a yielding bridge spanning the longitudinal slit in the piston skirt.

The piston structure shown in Fig. 1 to 100

Fig. 4, inclusive, of the drawings illustrates one application of the invention wherein the piston comprises a head 20 that has suitable piston ring receiving grooves formed therein, and a skirt structure that is carried solely from one side of the head.

The oppositely positioned skirt portions 21 and 22 take the lateral component of thrust from the connecting rod and are 10 termed herein the working faces of the piston skirt. Working face 21 is supported from the head whereas working face 22 is supported solely from working face 21 by the oppositely positioned segmental connectors 15 23 and 24 of the piston skirt. The working face 22 is yieldingly connected to the working face 21 by the radially flexible character of the web 24, and the yielding relation of the severed parts of the connector 23 that has 20 a longitudinal slit 25 extending the entire length thereof.

An arch member 26 straddles the slit 25 on the inner side of the piston skirt to yieldingly connect the severed parts of the skirt element 23, as shown in Fig. 4, and to provide a mutual support for the severed portions of the connecting element 23. Any tendency to longitudinal movement of the working face 22 relative to the working face 21 is effectively resisted by the relatively wide connecting arch 26 whereas the arch connector 26 will flex sufficiently in response to cylinder pressure on the working face 22 of the skirt to prevent scoring or seizing of the piston.

35 The connecting arch also provides a mutual support for the severed portions of the skirt member 23 that facilitates finishing the piston to truly cylindrical or tapered cylindrical form. The casting strains that are 40 generally present in a piston structure cause the severed skirt elements to move slightly out of alignment with each other when a slit is formed that separates the skirt longitudinally. The arch member supports each of 45 the severed parts from the other severed part and thereby prevents objectionable local flexing of the slit portions 23 of the skirt under the pressure of machine tools or of the grinding machine.

50 A longitudinal skirt stiffening or reinforcing rib 28 is formed on the inner side of the working face 21 of the skirt and extends to and joins with the head 20 of the piston to longitudinally reinforce the supported working face of the skirt and to form a more rigid longitudinal connection between the head and the working face 21. The necessity for and the form and extent of the reinforcing rib 28 depends upon the degree of rigidity and 55 strength that is necessary to support the working face 21 of the skirt from the piston head and also to give the working face 21 sufficient strength and rigidity to properly carry the working face 22.

60 65 In order to balance the piston, the working

face 22 may be formed a sufficient degree thicker than the working face 21 to substantially balance the weight of the piston structure about the axis of the wrist pin. The skirt 22 is preferably made of increased thickness from the connector 23 to the center of the working face 22.

The particular feature of the piston structure that is emphasized herein is the support of one only of the working faces of the skirt and the complete operative separation of the other working face of the skirt from both the head and the piston bosses beyond the longitudinal median plane of the piston passing through the wrist pin axis. The working face 22 of the piston described is carried solely from the working face 21. One working face is rigidly carried whereas the other face is yieldingly carried by the piston structure.

The above described piston can be fitted with reasonable snugness to the cylinder in a cold engine. The mechanical tolerance of fit is thereby greatly reduced for quantity manufacture because the flexing of the piston skirt will take care of considerable variation in different relative cylinders and piston faces. The skirt will yield sufficiently from the cylinder wall pressure to take a good polish without scoring in a properly finished cylinder even when the piston is fitted to the cylinder tighter than is necessary for satisfactory operation.

The substantially rigid connection of the working face 21 to the piston head makes it desirable, although not necessary, to mount the piston with the working face 21 so disposed as to take the side thrust of the explosive stroke whereas the less rigidly carried working face 22 is connected to the piston structure with sufficient rigidity to take the side thrust on the compressive stroke of the motor without substantial flexing. The presence of the single longitudinal slit 25 in the piston skirt and the twist resisting quality of the yielding arch 26 provides a very satisfactory connection for transmitting side thrusts from the working face 21 to the working face 22 of the skirt. The presence of the longitudinal slit 26 in the connecting portion 23 of the skirt renders the skirt uniformly flexible around its periphery and in the direction of both of its principal diameters.

Considerable pressure is ordinarily required to break down the oil film between the piston and the cylinder walls because of the large area of the working faces of the piston. When diametral forces from the direction of the wrist pin as well as at right angles thereto act to compress the piston, the piston structure can be made much stiffer than in pistons that are substantially compressible only along one major diameter. This stiffer structure provides the more satisfactory struc-

ture for the transmission of lateral connecting rod thrust.

The form of piston shown in Fig. 5 and Fig. 6 has the longitudinal slit 30 formed in the rigidly supported working face 31.

5 This form of piston may either be provided with an internal flexible arch 32 that permits closing in of the slot under compressive forces from the cylinder wall, or the piston 70 may be formed without a connection across the slit as shown in Fig. 7. The remainder of the structure of the pistons shown in Fig. 5, Fig. 6 and Fig. 7 is substantially the same as the piston shown in Fig. 1 to Fig. 4, inclusive.

10 15 When the longitudinal slot is formed in the working face 31, the separated parts of the working face readily flex from radially applied pressure on every diameter of the 20 piston, i. e. both in the longitudinal plane of the wrist pin and at right angles thereto.

25 Fig. 8, Fig. 9 and Fig. 10 illustrate a form of piston embodying the invention wherein the rigidly supported working face 33 of the piston is formed integrally with the head and a pair of oppositely disposed boss carrying webs 34. The opposed wrist pin bosses 35 are rigidly carried from the head. This provides a very strong support for this 30 working face 33 of the piston. The working face 36 of the skirt is carried solely by the opposed skirt elements 37 that are integrally formed with the working face 33 and working face 36.

35 The side wall of the head of this piston structure may be somewhat thickened at 38 to substantially balance the piston about the axis of the wrist pin.

40 The piston structure shown in Fig. 11 and Fig. 12 differs from the previously described piston by having a yielding arch member 39 spanning the longitudinal slit 40 of the skirt and also by having a slot 41 formed between the more rigidly supported working face 42 and the piston head. The working face 42 of the piston skirt is supported solely from the webs 43 and the working face 44 is supported solely by connecting skirt portions 45. The entire skirt is maintained at a cooler operating temperature by 45 arranging the slot between the top of the skirt and the head.

50 In this form of piston, the weight of the arch member 39 assists in balancing the piston about the axis of the wrist pin. The piston can also be counterbalanced on the side of the yielding working face by thickening the side wall of either the head or the working face of the skirt.

55 60 The piston structure shown in Fig. 13 and Fig. 14 is the same as the piston shown in Fig. 11 and Fig. 12 except that there is no yielding arch spanning the slit 46 of the working face 47 and that a chordal rib 48 is formed across the working face 49. This

minimizes flattening of the working face 49 from thermal expansion of the piston head and causes the skirt supporting webs 50 to take up the head expansion without transmitting it to the skirt. These webs are made sufficiently thin to flex sufficiently to take up the head expansion without materially twisting the wrist pin bosses 51.

70 The piston structure shown in Fig. 15 is the same as the structure shown in Fig. 13 and Fig. 14 except that the longitudinal slits 52 and 53 are formed in the skirt in a zone that is offset from both the working face 54 and the wrist pin boss 55. The slit 52 is spaced from the slit 53 substantially the same or somewhat less than the thickness of the skirt wall. This provides a yielding element 56 that permits closing in of the skirt under cylinder pressure.

75 80 The piston shown in Fig. 16 has the longitudinal slit 57 formed in the skirt underlying the wrist pin boss and spanned on the interior of the piston by a yielding arch 58. The piston is otherwise similar to the piston shown in Fig. 13 and Fig. 14.

85 It will be seen that in each of the foregoing piston structures, the piston skirt is so formed that it is radially compressible both in the direction of the wrist pin bosses and transversely relative thereto. In conventional forms of split skirt pistons with which applicant is familiar, the piston skirt is only compressible along one principal diameter. By making one working face responsive to compressing forces in the direction of the wrist pin bosses and at right angles thereto, the skirt can be made relatively stiffer and more capable of transmitting the side thrust from the connecting rod to the flexible working face without distortion of 100 the piston skirt.

105 The counterbalancing of the piston structure so that the weight on each side of the wrist pin will be substantially the same can obviously be accomplished by adding material to any desired part of the lighter side of the piston. The center of gravity of each side relative to the wrist pin axis should be maintained substantially the same in various piston structures.

110 115 In each of the above forms of piston, little attention need be given the tolerances for the piston fittings. The structure is so formed that it will inherently accommodate itself if fitted too closely to the cylinder walls.

120 Other benefits that are to be derived from practicing the invention will be apparent from a consideration of the foregoing specification and drawings of the various applications of the invention.

125 What I claim is:

1. A piston for an internal combustion engine comprising a head having depending wrist pin carrying bosses formed integrally therewith, a skirt portion integrally joined 130

to the head independently of said bosses having a primary working face carried thereby, a skirt portion having a secondary working face carried solely by circumferentially extending segments of said primary skirt portion spaced from said head, and a longitudinal split separating the secondary skirt portion from the primary skirt portion.

2. A piston for an internal combustion engine comprising a head, wrist pin bosses carried solely by said head, a skirt carried by said piston head solely from one working face thereof and joined to the head independently of said wrist pin bosses, and circumferentially extending segments spaced from said head and integrally united with said working face for solely supporting the other working face in free and unattached position relative to other parts of the piston structure, one of said segments being slotted to allow diametric yielding of said skirt without associated increase of its diameters at other points.

3. A single piece piston for an internal combustion engine comprising a head, wrist pin bosses relatively rigidly connected to said head, a skirt portion connected to said head at one side only and independently of said wrist pin bosses, said skirt portion being continuously separated from said head over materially more than 180 degrees of its circumference, circumferential segments spaced from said head and formed of the metal of said side integrally connected with the other side of said skirt to support the same independently of other parts of said piston structure, one of said segments being split to permit yielding of said skirt, and an integral arch member straddling the split in said segment to yieldingly connect the severed portions of said segment.

4. A piston for an internal combustion engine comprising an integrally formed head and skirt, the skirt being provided with diametrically opposite working faces and being connected to the head through only one of said working faces, the other working face being carried from the first named working face of the skirt by circumferential continuations of the same in unattached positive relation to the other parts of the piston, and a longitudinal split separating the working faces.

5. A piston for an internal combustion engine comprising an integrally formed head and skirt, the skirt being provided with diametrically opposite working faces and being connected to the head through only one of said working faces, the other working face being carried from the first named working face of the skirt by circumferential continuations of the same in unattached positive relation to the other parts of the piston, a longitudinal split separating the working faces, and an integral member straddling the split

to yieldingly connect the severed portions of said piston.

In testimony whereof I affix my signature.

WILLIAM C. MCCOY.
